FLOW ARRANGEMENT FOR MULTIPASS
HEATERSJohn W. Throckmorton, New York, N. Y., assignor
to Petro-Chem Process Company Inc., New
York, N. Y., a corporation of Delaware

Application June 16, 1950, Serial No. 168,556

6 Claims. (Cl. 257—255)

1

This invention relates to an improved heating tube arrangement for a single bank of tubes having a multi-pass flow, and more particularly pertains to such an arrangement in which one pass or row of tubes is tipped relative to the other so that sufficient space is left between the ends of the tubes to connect successive tubes of the same pass by straight-line U bends or straight-line plug type headers, i. e. by bends or headers which are not offset relative to the tubes to which they are connected.

In heaters employing a bank of tubes substantially in one plane and exposed on both sides to the furnace seat, it is a simple matter and no difficulties have been encountered when the tubes are interconnected at their ends for continuous series flow since the usual form of return bends of the U type are available and suitable for this purpose.

However, it is frequently desirable to interconnect the tubes for multi-pass flow and then the normal return bends cannot be employed because the bends of one pass interfere with the tubes pertaining to the other pass. Special offset return bends or headers have been used to avoid such interference but they introduce other difficulties since they cause a relatively sudden change in the direction of flow at the special return bends and thus increase the back pressure in the system and tend to cause excessive erosion at the return bends. Not only are these offset headers very expensive, but much furnace efficiency is lost thereby, due to high pressure drop of charging stock as it passes through the tortuous path of the offset header.

It is therefore an important object of the invention to provide an improved flow arrangement for a multi-pass bank of heating tubes of less expensive construction than in arrangements heretofore employed.

It is another object to provide a flow arrangement for a multi-pass heater in which excessive erosion caused by offset headers or return bends is eliminated.

It is a further object to provide a flow arrangement for a multi-pass heater in which the pressure drop of the charging stock is substantially less than in arrangements heretofore employed.

The above and other objects and advantages will appear more clearly in connection with the following description taken in conjunction with the accompanying drawings in which:

Fig. 1 illustrates in perspective a two-pass arrangement embodying the invention in which the tubes of each pass are joined at alternate ends by U bends;

Fig. 2 is substantially an end view of the arrangement of Fig. 1, but the tubes of each pass

2

are joined at alternate ends by plug-type headers, the latter being shown schematically;

Fig. 3 is a view of the headers of Fig. 2 as seen from line 3—3;

Fig. 4 illustrates in some detail a plug-type header suitable for use in the arrangement of Fig. 2; and

Fig. 5 is a view corresponding to Fig. 3 of an arrangement heretofore in common use, in which offset headers are employed.

It is at times desirable to use, in a furnace construction, a single bank of straight tubes with a two-pass flow. In such a bank, the tubes of the first pass alternate with the tubes of the second pass, and the tubes of each pass are joined at alternate ends.

Referring to Figs. 1 and 2 of the drawings, Fig. 1 is a perspective view of a tube arrangement embodying the invention. A first pass 4 comprises a plurality of evenly spaced, straight, parallel tubes 6, shown as coplanar, having an inlet 8 and an outlet 10. The alternate ends of the tubes 6 are joined by straight-line U bends 12 (that is, they are coplanar with their pass 4) to form a continuous path for flow of charging stock from the inlet 8, through the tubes 6 and the bends 12 and thence to the outlet 10.

A second pass 14, similar to the first pass 4, comprises a plurality of evenly-spaced, straight, parallel tubes 16, shown as coplanar, having an inlet 18 and an outlet 20. The alternate ends of the tubes 16 are joined by straight-line U bends 22, to form a continuous path for flow of charging stock from the inlet 18 through the tubes 16 and thence to the outlet 20.

The tubes 16 of the second bank 14 and the tubes 6 of the first bank 4 are alternately spaced.

The line defined by the midpoints of the tubes 16 of the second pass 14 coincides with the line 40 defined by the midpoints of the tubes 6 of the first pass 4, and the plane defined by the second pass 14 is slightly tipped with respect to the plane defined by the first pass 4, about the above-mentioned line. This is to provide space at the ends of the tubes 6 and 16 for the U bends 12 and 22, which are significantly not offset but lie in the planes defined by their respective banks 4 and 14. Thus offset headers do not have to be used, and the pressure drop of the charging stock in passing from one tube to the next is held to a minimum.

Fig. 2 substantially illustrates in end view the arrangement of Fig. 1, with a principal exception to be noted below. Two straight tubes 24 and 26, the latter behind the former, represent two passes 28 and 30, respectively. An axis 32 perpendicular to the tubes 24 and 26 is defined by their mid-

points and the tube 26 is rotated slightly about the axis 32.

The only difference between the arrangement of Fig. 2 and that of Fig. 1 is that in the former, the tubes of the passes 28 and 30 are joined at alternate ends by straight-line plug-type headers 34 and 36, respectively, instead of by the U bends 12 and 22 of the latter.

Fig. 3 shows two each of the upper plug-type headers 34 and 36 of the passes 28 and 30, respectively, of Fig. 2, as seen from line 3—3 thereof, but omitting the portions of the tubes 24 and 26 between line 3—3 and the headers 34 and 36. Only one each of the headers 34 and 36 is visible in Fig. 2.

The openings in all the headers 34 for insertion of the tubes 24 lie in a straight line 38—38; likewise, the openings in all the headers 36 for insertion of the tubes 26 lie in a straight line 40—40, parallel to and separated in practice by only a few inches from the line 38—38. It is because of this separation that the headers 34 and 36 may be of the straight-line type.

The headers 34 and 36 appear in Fig. 3 to be slightly bulged outward in their central portions. This is because the planes of the headers are not perpendicular to line 3—3, due to the slight tipping of the tubes 24 and 26 relative to each other.

A conventional straight-line plug-type header 42 suitable for use in the arrangement of Fig. 2 is shown in Fig. 4. The header 42 comprises a semi-circular tubular body portion 44, with an opening 45 in each end 46 thereof for the insertion of parallel heating tubes 48. The entire body portion 44 lies in the plane defined by the tubes 48. In line with the openings 45, but on the outer side of the body portion 44, are two built-up openings 50, each of which carries a plug 52, which may be removed in order to gain access to its corresponding tube 48.

The internal configuration of the body portion 44 is essentially smooth, in spite of the openings 50.

In both Fig. 1 and Fig. 2, the tubes cross each other at their midpoints, and if intermediate supports are necessary, such supports would be standard for each tube of each pass.

Many commercial heaters employ tubes which may vary from 20 to 30 feet in length and it is therefore apparent that the tubes may make up a bank which is substantially in a single plane even though the tubes are connected in groups with the tubes of one group mounted in one plane which crosses the plane of the other group at a very small angle but quite sufficient to enable straight line return bends to be employed at the ends of the tubes. Figure 2 of the drawings exaggerates the angle which would normally exist between the tube planes.

Fig. 5 is a view similar to Fig. 3, but of an arrangement of the prior art. The ends of tubes (not shown) of two passes 54 and 56 lie in a straight line 58—58, necessitating the use of offset headers 60 and 62, with their inherent disadvantages noted above, to connect the alternate ends of the tubes of the passes 54 and 56, respectively.

Thus the invention is well adapted to attaining its objects, and many disadvantages of the prior art are overcome. The need for the expensive offset headers is obviated, the pressure drop of the 70 charging stock in passing from one tube to the next is greatly reduced, and excessive erosion caused by offset headers or return bends is eliminated.

Obviously many modifications and variations of 75

the invention, as hereinbefore set forth, may be made without departing from the spirit and scope thereof, and therefore only such limitations should be imposed as are indicated in the appended claims.

Having thus described my invention, I claim:

1. A bank of heating tubes having a multi-pass flow, comprising a first pass including a plurality of straight tubes joined at alternate ends by straight-line return means, a second pass including a plurality of straight tubes joined at alternate ends by straight-line return means, the tubes of said second pass alternating in said bank with the tubes of said first pass, a centrally located straight line defined by centrally located points of all said tubes, said second pass being tipped with respect to said first pass about said line.

2. A bank of heating tubes having a multi-pass flow, comprising a first pass including a plurality of coplanar straight, parallel tubes joined at alternate ends in series by straight line return means, a second pass including a plurality of coplanar straight, parallel tubes joined at alternate

ends in series by straight-line return means, the tubes in said second pass alternating in said bank with the tubes of said first pass, a straight line defined by the longitudinal midpoints of all said tubes, the plane defined by said second pass intersecting the plane defined by said first pass on said line.

3. A bank of heating tubes having a multi-pass flow comprising a first pass and a second pass, each said pass including a plurality of straight, parallel tubes disposed alternately with the tubes of the other pass, the tubes of said first and second passes defining, respectively, a first plane and a second plane, said first plane intersecting said second plane along a line defined substantially by the longitudinal midpoints of all said tubes, said first plane making a small angle with said second plane, and straight-line return means connecting the tubes of said first and second passes at alternate ends.

4. The invention set forth in claim 3 wherein said straight-line return means are plug-type headers.

5. The invention set forth in claim 3 wherein said straight-line return means are U bends.

6. A bank of heating tubes having multi-pass flow, comprising a plurality of passes, each pass composed of a plurality of coplanar straight parallel tubes, the adjacent ends of which are joined by coplanar U shaped passages, the plane of said passages being the same plane as that of said tubes, the tubes of each pass being interleaved alternately with the tubes of the other pass, and the plane of each pass intersecting along a line defined by the longitudinal mid-points of all of the tubes.

JOHN W. THROCKMORTON.
